[57] CLAIM

The ornamental design for an roller conveyor belt for curved path, as shown and described.

DESCRIPTION

FIG. 1 is a top plan view of the roller conveyor belt for curved path showing my new design;

FIG. 2 is a fragmentary axonometric view thereof as viewed from the larger radius end, the belt being fragmentarily shown for convenience of illustration; and FIG. 3 is a fragmentary axonometric view thereof as viewed from the smaller radius end, the belt being fragmentarily shown for convenience of illustration.

The rollers are partially shown in FIGS. 2 and 3 for convenience of illustration, it being understood that they are continuous around the belt as indicated in FIG. 1.

FIG. 1.

FIG. 2.

FIG. 3.
